No. 37,325.

Patented February 7, 1905.

UNITED STATES PATENT OFFICE.

GEORGE E. SAVAGE, OF MERIDEN, CONNECTICUT, ASSIGNOR TO
MANNING, BOWMAN & COMPANY, OF MERIDEN, CONNECTI-
CUT, A CORPORATION OF CONNECTICUT.

DESIGN FOR A COVER FOR CHAFING-DISHES OR SIMILAR ARTICLES.

SPECIFICATION forming part of Design No. 37,325, dated February 7, 1905.

Application filed January 9, 1905. Serial No. 240,363. Term of patent 7 years.

To all whom it may concern:

Be it known that I, GEORGE E. SAVAGE, a citizen of the United States, residing at Meriden, county of New Haven, State of Connecticut, have invented a new, original, and ornamental Design for a Cover for Chafing-Dishes or Similar Articles, of which the following is a specification.

The drawing is a perspective view of a cover

for chafing-dishes or similar articles embodying my design.

What I claim is—

The ornamental design for a cover for chafing-dishes or similar articles as herein shown.

GEORGE E. SAVAGE.
